CLAIM

The ornamental design for a solar-charging mounting bracket for video doorbell, as shown and described.

DESCRIPTION

FIG. 1 is a front, top, right-side perspective view of a solar-charging mounting bracket for video doorbell;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines depict features of the solar-charging mounting bracket for video doorbell that form no part of the claimed design.

1 Claim, 5 Drawing Sheets
